DESIGN FOR A LIFTING JACK

Marcellus S. Merrill, Denver, Colo.

Application September 20, 1937, Serial No. 71,691

Term of patent 7 years

To all whom it may concern:

Be it known that I, Marcellus S. Merrill, a citizen of the United States, residing at Denver, in the city and county of Denver, and State of Colorado, have invented a certain new, original, and ornamental Design for a Lifting Jack, of which the following is a specification, reference being had to the accompanying drawing, forming part thereof.

I claim:

The ornamental design for a lifting jack, as shown.

MARCELLUS S. MERRILL.
